UNITED STATES PATENT OFFICE.

ISAIAH WASHINGTON BROMON, OF WILKINSBURG, PENNSYLVANIA.

STOVE.

Application filed August 16, 1923. Serial No. 657,792.

To all whom it may concern:

Be it known that I, ISAIAH WASHINGTON BROMON, a citizen of the United States, and a resident of Wilkinsburg, in the county of 5 Allegheny and State of Pennsylvania, have invented a new and Improved Stove, of which the following is a full, clear, and exact description.

This invention relates to stoves, ranges 10 and the like and has for an object to provide a construction wherein a maximum amount of heat is absorbed by the articles being heated or cooked.

Another object of the invention is to provide 15 a gas stove arranged with pockets and associated parts whereby excess heat from one pocket may pass to another pocket and thereby permit a more efficient absorption of the heat units while the stove is in use.

20 A still further object, more specifically, is to provide a stove with a plurality of burners and pockets surrounding the burners with connecting tubes whereby the heat from one pocket may be caused to pass 25 to another pocket before it escapes to the draught.

In the accompanying drawings—

Figure 1 is a side view of a gas stove, disclosing an embodiment of the invention.

30 Figure 2 is a top plan view of the stove shown in Figure 1.

Figure 3 is a sectional view through Figure 1, approximately on line 3—3, the same being on an enlarged scale.

35 Figure 4 is a sectional view through Figure 2, on line 4—4, the same being on an enlarged scale.

Figure 5 is a perspective view of a spacing liner, embodying certain features of 40 the invention.

Referring to the accompanying drawings by numeral, 1 indicates a gas stove of any desired construction as far as the oven and general shape is concerned. Heretofore, in 45 gas stoves, a suitable burner was provided and above the burner openings were formed, said openings being usually covered by a grating of some kind for supporting a pan or other article. This former structure by 50 reason of this open formation, permitted a large quantity of the heat units to escape laterally and also escape around the pan or other article being heated so that the efficiency thereof was low. In order to increase the efficiency and to utilize as many 55 of the heat units as possible, the present in-

vention includes a number of pockets which are indicated in the drawing as 2, 3, 4 and 5. It is, of course, understood that there may be more or less pockets if preferred. 60 Each of these pockets is formed with a tubular section having straight walls and a curved lower end which is adapted to receive a burner 6, which burner may be of any desired type. The lower rounded end 65 of each of the pockets 2 is provided with a number of air holes 8 whereby ample air is provided for securing the desired combustion of gas.

In each pocket a number of supporting 70 arms 9 are provided designed to support a disk 10 of some suitable refractory material, as for instance, fire clay. This disk is provided with a number of perforations to permit a large percentage of the flame to pass 75 therethrough. This arrangement of pocket and disk 10 is such that the disk 10 becomes incandescent and, consequently, will consume most, if not all, of any soot or carbon produced by the burner when said soot 80 strikes the incandescent disk. Arranged at a desired point above the arms 9 is a second set of arms 11 adapted to support an article to be heated, as for instance, a sauce pan 12 or other container. The arms 11 may, under 85 some circumstances, support a liner 13, which liner is used when a shallow pan is supported in the pocket in order that the upper part of the pan may project above the pocket. Preferably when either a deep 90 container similar to container 12 is used or a shallow container, means are provided for preventing the passage of any of the flame or heat units out of the top of the pocket. This means consists of an annular ring 13 95 of asbestos or other desired material which is preferably L-shaped in cross section and which, when in use, is positioned as shown at the left in Figure 4.

By this construction and arrangement, the 100 heat is applied to the bottom of the container and to the sides but practically none can escape out the top of the pocket. In order to provide a proper outlet or draught for the products of combustion, tubular passage-ways 14, 15, 16, 17 and 18 are provided. The passage-ways 17 and 18 merge together as shown in Figure 3 and also merge 105 into the outlet passage-way 19 which is connected with the draught or smokestack 20. Dampers 21, 22, 23, 24 and 25 are arranged 110 in the various passage-ways and controlled

by suitable control rods 26 extending to the front of the stove. In case the pockets 3 and 4 are used, dampers 23 and 24 would be opened and the remaining dampers closed as shown in Figure 3. This would cause the products of combustion to pass from the pocket 3 to pocket 4 and from thence to the outlet 19 so that pocket 4 would receive some of the heat from pocket 3. It will be understood that the dampers 23 and 24 will be opened only to the proper extent to secure a proper draught for maintaining a desired combustion.

Under some circumstances, the pocket 2 might be used and the burner 6 thereof used while the pockets 3 and 4 might be used without the burners therein being lighted. It will, of course, be understood that most of the heat would be applied to the article arranged in pocket 2 but an appreciable amount of heat would be also applied to the articles of the pockets 3 and 4 for slowly cooking the same or for maintaining the same warm so that one burner would function in a certain sense as three burners. In case a flat article was to be heated, as for instance, an ordinary skillet which was too big to enter the pocket and rest on the liner 13, it could be placed directly on top of the pocket and receive heat therefrom substantially in the usual manner except that the excess heat would pass out through one of the passage-ways extending from the pocket. In order to provide a proper pocket for the stove, covering plates 27 might be provided and supported by cross bars or any suitable means. In the drawings, four plates 27 have been provided but it will be evident that a single plate might be used, or more than four. In regard to the oven of the stove, pockets similar to pocket 2 might be used or a burner of the old type provided as preferred.

What I claim is:—

45 1. A gas stove, comprising a body, a plurality of pockets carried by the body, tubular members connecting said pockets, a damper arranged in each of the tubular members, a burner arranged in the lower part of each of the pockets, a plurality of brackets in each pocket for supporting an article to be heated, and a packing member adapted to surround the article to be heated, said packing member being positioned adjacent the top of the pocket whereby excess heat and products of combustion will be caused to pass through certain of said tubular members to adjacent pockets.

60 2. In a gas stove, a pocket substantially tubular open at one end and closed at the

opposite end except for air holes, a burner arranged in the closed end of said pocket, a plurality of sets of supporting arms arranged in the pocket positioned in different planes, one set of arms being adapted to support an article to be heated, and a refractory disk arranged on the other of said arms adapted to be heated to incandescence for causing a more thorough combustion.

3. In a gas stove, a tubular pocket structure, a gas burner arranged in the bottom of said pocket structure, a plurality of supporting arms arranged in said pocket structure above the burner, a liner cage mounted on said supporting arms whereby a comparatively shallow article may be supported in the pocket and permitted to project thereabove.

4. In a gas stove, a tubular pocket, a burner arranged in the lower part of said pocket, a plurality of arms arranged in said pocket above the burner, and a comparatively thin perforated disk of refractory material mounted on said arms, said disk being adapted to become substantially incandescent when said burner is in use for assisting in the combustion of the gas supplied to the burner.

5. A gas stove, comprising a body, a plurality of pairs of burners, a pocket for each of said burners, tubular members for connecting said pockets together so that products of combustion may pass from one pocket to the other, a draught pipe connected to one of said tubular members, a valve arranged in the last mentioned tubular member on each side of the entrance thereof into the draught pipe, a damper arranged in each of the other tubular members, and independent manually actuated members for opening and closing said dampers whereby products of combustion may be directed to said draught pipe from any of the burners.

6. A gas stove, comprising a body, a plurality of pockets substantially tubular in shape, tubular connecting members connecting the upper parts of said pockets together so that products of combustion may pass from one pocket to the other, a pair of supporting arms arranged in each pocket beneath the tubular connecting members whereby heat and products of combustion rising from the bottom of the pockets must pass around the articles to be heated before it can enter said connecting tubular members, and a heater arranged in the bottom of each of said pockets.

ISAIAH WASHINGTON BROMON.
